DISTILLATION OF LUBRICATING STOCK

Filed April 14, 1926

UNITED STATES PATENT OFFICE.

ALBERT G. PETERKIN, JR., OF BRYN MAWR, WILLIAM F. STROUD, JR., OF CYNWYD, AND RICHARD B. CHILLAS, JR., OF PHILADELPHIA, PENNSYLVANIA, ASSIGNEES TO THE ATLANTIC REFINING COMPANY, OF PHILADELPHIA, PENNSYLVANIA, A CORPORATION OF PENNSYLVANIA.

DISTILLATION OF LUBRICATING STOCK.

Application filed April 14, 1926. Serial No. 101,857.

Our invention relates to the distillation of oils and more particularly to a process of distilling mineral oils without substantial cracking.

5 In accordance with our invention there is admixed with crude petroleum, petroleum distillate or residuum lower boiling oil, and the mixture is rapidly heated to a temperature in excess of its usual or normal cracking temperature to vaporize a substantial portion of the mixture, the vapors being kept in contact with the liquid oil until the maximum temperature is reached, and the vapors are then separated from the liquid, and the 10 liquid oil is immediately cooled to a temperature below the cracking temperature, or to a temperature which with attendant conditions will prevent cracking.

Further, in accordance with our invention, 20 a petroleum product containing substantial quantities of lubricating stock, such as paraffine distillates or the like containing substantial quantities of high viscosity lubricating stock, is mixed with lower boiling oil as 25 naphtha and subjected to treatment of the character above referred to. This process yields, without substantial cracking, a liquid oil residuum or bottoms constituting a satisfactory lubricating stock or heavy cylinder 30 stock.

Further, a distillate containing substantial quantities of lubricating stock may be procured from distillation of crude petroleum or suitable petroleum product in a method of 35 the character described in our co-pending application Serial No. 34,750, filed June 4, 1925, and then re-run in dilution with naphtha or the like, in accordance with this process, to yield a heavy lubricating or cylinder stock as 40 residuum or bottoms.

Our invention resides in a method of the character hereinafter described and claimed.

This application is in part a continuation of our prior application, Serial No. 34,750, 45 filed June 4, 1925, which covers a general method of distillation of oils. This general method is not directly applicable to the distillation of certain crude petroleums or petroleum products which are deficient in low 50 boiling materials and which cannot, therefore, be distilled to a desirable percentage bottoms without running to such high temperature that cracking occurs even by the use

of the process described in said prior application. In accordance with the present invention this deficiency of low boiling compounds is overcome by the addition of a lower boiling oil, which has the effects of lowering the temperature to which the oil must be heated in order to produce the desired bottoms and of ensuring in the still or heating structure the desired degree of turbulence and velocity by vaporization of the added lower boiling oil. This lower boiling oil may be a distillate, as, for example, naphtha, or 60 may be an oil of the general character of the oil to be distilled, but richer in low boiling compounds, distilling, for example, below 500° F. We have found that when distilling oils showing less than 30% distillate 65 below 500° F. by the distillation method 70 D86—25T, A. S. T. M. Tentative Standards, 1925, page 325, it is frequently advisable to adjust the content of these low boiling materials by the addition of a naphtha or other 75 lower boiling oil, so as to bring the amount distilling below 500° F. to at least 30%.

The type of oil to be treated generally benefiting by such admixture is such an oil which by the vacuum assay distillation test, as described in Industrial and Engineering Chemistry, 1925, vol. 17, No. 12, page 1248, will show under an absolute pressure of 10 m. m. (Hg) at least 20% residuum at 650° F.

For an understanding of our process and 85 for an illustration of an apparatus utilizable for practice of the same, reference is made to the accompanying drawing, in which:

H is an oil heater of any suitable type, comprising tubes T disposed in the tube chamber 90 A, whose lower end communicates with a stack or flue a and into whose upper end are discharged from the combustion chamber B the hot gases and products of combustion resulting from the burning of any suitable fuel, 95 as oil or gas, delivered to the burner b.

The petroleum or petroleum product diluted with lower boiling oil as naphtha or equivalent, is delivered through the pipe c to the pump P which delivers it at suitable 100 pressure to the inlet of the tube system T through which it rises counter current to the descending hot gases and is discharged through the pipe d into the chamber C, which, in the example illustrated, is a fractionating 105 column or tower, having, for example, the

well-known fractionating plates D, vapor uptake 1, bubbler caps 2 and reflux pipes or tubes 3. The lower portion of the column or chamber C is in effect a vapor box. The oil discharge d into the chamber C is preferably disposed at a point one or more plates above the bottom chamber or section M.

The oil charged through the pipe c may be cold or it may be preheated, as by absorption of heat in any one or more of the oil or vapor cooling structures hereinafter described, and is raised in temperature within the tube or pipe system T to a temperature in excess of cracking temperature, as for example, of the order of 700 or 800° F. or higher, and passes through the tube structure at a velocity sufficiently high to shorten the period of traverse of the heating zone to an extent sufficient to inhibit substantial cracking. Vapors are liberated in the oil within the tube structure, and these, assisted by the velocity of the oil as delivered by the pump P, serve to effect turbulence of the oil, thereby enhancing the rate of heat transfer to the oil. The pressure of the oil as delivered by the pump P is at least such as to maintain the desired velocity of the oil through the tube system, the magnitude of the pressure at the entrance into the tube system being determined principally by the length and cross section of the tubular passage.

With the bottom of the chamber C communicates the pipe e, through which is delivered steam, preferably previously superheated, as in a superheater E. Communicating with the bottom of the tower C is the pipe f disposed preferably in the form of a trap g at suitable distance vertically below the pipe h, which delivers the bottoms through a cooler F to the storage tank S.

Connected with the upper end of the column C is the pipe i conducting vapors to the condenser G cooled by any suitable medium, as, for example, water, introduced at j and discharged at k. The condensate, comprising oil and water, is delivered through the pipe m, controlled by valve n, to the water separator I, in which the oil and water separate, the water passing off through the trapped pipe o. The oil passes off through the pipe p to the flow box J in which the oil is divided in any desired proportions into two streams, one of which passes off through the pipe q to the storage tank S³, and the other of which passes through the trapped pipe r into the upper end of the column C as a reflux stream which flows downwardly through the column countercurrent to the rising vapors.

From suitable different altitudes within the column C may be withdrawn various desired fractions or cuts in liquid form, through, for example, the several pipes t and u, delivering through associated coolers K¹ and K², respectively, to the storage tanks S¹ and S².

The oil-vapor mixture entering the tower C at d comes into contact with the steam delivered through the pipe e, and is thereby immediately cooled to a temperature below the cracking temperature, or in any event, to a temperature which with the attendant conditions within the tower prevents cracking. The steam in the presence of the hot liquid oil causes part of the liquid oil to vaporize, and the vaporization so induced effects the cooling aforesaid by abstracting from the liquid oil the necessary latent heat of vaporization.

The unvaporized oil flows downwardly in the tower C, while in intimate contact with the upwardly flowing steam, accumulating at the lower end thereof as bottoms, with resultant vaporization of lower boiling point components, which imparts to the bottoms a higher flash test. The bottoms are continuously or at suitable intervals drawn off through the cooler F to the storage tank S.

The mixture of oil vapors and steam flows upwardly through the tower, being brought in the course of its flow into intimate contact with the down flow of liquid through the tower and effecting the necessary interchange for fractionation. The liquid is drawn off as various fractions through pipes t and u, the heavier fractions at the lower altitudes and the lighter fractions at the higher levels. The lightest vapors pass through the pipe i to the condenser G, the condensate eventually reaching the flow box J, which divides the condensate stream, part passing through the pipe q to the storage tank S³ as aforesaid, and a suitable portion of the condensate being refluxed through the pipe r to the tower.

As above indicated, the oil treated may be petroleum distillate containing substantial quantities of lubricating stock and may include paraffine distillates or high viscosity distillates obtained from coking crudes which ordinarily do not yield a cylinder stock due to the relatively large asphaltic content. In accordance with our process the bottoms or residuum in the column C and delivered to the storage tank S is cylinder stock or other heavy lubricating stock which is relatively clean, because the starting material is a distillate, therefore requiring less acid treatment and, therefore, maintaining higher viscosity and reducing loss of oil or stock attendant upon acid treatment.

In the distillation of a crude petroleum, for example a mid-continent or mixed base crude, in a system and by a method of the character described in our aforesaid application, Serial No. 34,750, there may be obtained a cut taken off from near the bottom of the column or tower C, representing a distillate, too heavy for satisfactory pressing for removal of paraffine wax. Such a distillate is commonly redistilled with little or no steam giv-

ing a suitable "paraffine distillate" fraction and bottoms suitable only for fuel. This cut, containing substantial quantities of lubricating stock and substantially no components 5 boiling below 500° F., may in accordance with our invention be re-run or redistilled in a system and process of the character above described, with improved results in that a clean uncracked bottoms results which is suitable 10 in every way for high grade cylinder stocks. The test below is characteristic of such bottoms by this process.

Gravity	21.1° A. P. I.
Viscosity @ 210° F. (Saybolt Universal)	150
Flash	540° F.
Fire	635° F.

In the commonly used methods the paraffine distillate is the only lubricating oil fraction obtained and its viscosity is much lower than that of the lubricating oil produced by 20 our method.

In connection with the re-running, by our 25 process, of a heavy overhead such as the above, containing, for example, a considerable percentage of oils with a Saybolt Universal viscosity of 100 seconds or above at 210° F., we add an amount of a naphtha fraction, boiling largely below 500° F. at atmospheric pressure, in an amount of the order of 30 60% of the charge.

The addition of the naphtha makes use of 35 the fact that the presence of the low boiling constituents has the effect of lowering the boiling point of the high boiling oils. By its use distillation to a definite percentage bottoms may be accomplished at a much lower temperature than is necessary without 40 it, and we are able to distill material which otherwise could not be distilled without the use of excessive quantities of steam, as it would decompose before reaching its boiling point. At the same time in the case of a pipe 45 still, when operating in accordance with the present process, on account of the greater proportion of vapor the linear rate of the flow through the tubes is increased, giving greater turbulence and shortening the time during 50 which the oil must be maintained at a high temperature. These three factors combine to minimize cracking.

What we claim is:

1. The method of distilling a hydrocarbon 55 oil characterized in that it leaves a residue of at least 20% when distilled to 650° F. under an absolute pressure of 10 mm. of mercury, which comprises admixing with the oil a petroleum distillate substantially all of which 60 will distil below 500° F. under atmospheric pressure, rapidly heating the mixture to a temperature in excess of that at which substantial cracking of the oil would occur if the mixture were permitted to remain at such 65 temperature for a prolonged period of time,

immediately thereafter separating from that portion of the mixture which remains liquid the vapors which form as a result of the heating aforesaid, then before substantial cracking occurs, passing the liquid so separated 70 into a zone substantially devoid of the separated vapors, and cooling it while in said zone to prevent cracking.

2. The method of distilling a hydrocarbon oil characterized in that it leaves a residue of 75 at least 20% when distilled to 650° F. under an absolute pressure of 10 mm. of mercury, which comprises admixing with the oil a petroleum distillate substantially all of which 80 will distil below 500° F. under atmospheric pressure, rapidly heating the mixture to a temperature in excess of 750° F., immediately thereafter separating from that portion of the mixture which remains liquid the vapors which form as a result of the heating 85 aforesaid, then before substantial cracking occurs passing the liquid so separated into a zone substantially devoid of the separated vapors, and bringing it while in said zone into contact with a gaseous medium for effecting 90 further separation of vapors and for cooling to prevent substantial cracking.

3. The method of distilling a hydrocarbon oil containing lubricating stock and characterized in that it leaves a residue of at least 95 20% when distilled to 650° F. under an absolute pressure of 10 mm. of mercury, which comprises admixing with the oil a petroleum distillate substantially all of which will distil below 500° F. under atmospheric pressure, rapidly heating the mixture to a temperature in excess of that at which substantial cracking of the oil would occur if the mixture were permitted to remain at such temperature for a prolonged period of time, immediately thereafter separating from that portion of the mixture which remains liquid the vapors which form as a result of the heating aforesaid, then before substantial cracking occurs 100 passing the liquid so separated into a zone substantially devoid of the separated vapors, and cooling it while in said zone to prevent substantial cracking and to effect a residuum 105 of lubricating stock.

4. The method of distilling a distillate of 115 hydrocarbon oil containing lubricating stock and characterized in that it leaves a residue of at least 20% when distilled to 650° F. under an absolute pressure of 10 mm. of mercury, which comprises admixing with the oil a petroleum distillate substantially all of which will distil below 500° F. under atmospheric pressure, rapidly heating the mixture to a temperature in excess of that at which substantial cracking of the oil would occur if the mixture were permitted to remain at such 120 temperature for a prolonged period of time, immediately thereafter separating from that portion of the mixture which remains liquid 125 the vapors which form as a result of the heat-

ing aforesaid, then before substantial cracking occurs passing the liquid so separated into a zone substantially devoid of the separated vapors and bringing it into contact with a 5 gaseous cooling medium while in said zone, for effecting further separation of vapors and for cooling to prevent substantial cracking, and to effect a residuum of lubricating stock.

5. The method of distilling hydrocarbon oil 10 characterized in that it leaves a residue of at least 20% when distilled to 650° F. under an absolute pressure of 10 mm. of mercury, which comprises admixing with the oil a petroleum distillate in such proportions that at 15 least 30% of the mixture boils below 500° F. at atmospheric pressure, rapidly heating the mixture to a temperature in excess of that at which substantial cracking of the oil would occur if the mixture were permitted to remain 20 at such temperature for a prolonged period of time, immediately thereafter separating from that portion of the mixture which remains liquid the vapors which form as a result of the heating aforesaid, then before substantial 25 cracking occurs passing the liquid so separated into a zone substantially devoid of the separated vapors, and cooling it while in said zone to prevent cracking.

6. The method of distilling a hydrocarbon oil characterized in that it leaves a residue 30 of at least 20% when distilled to 650° F. under an absolute pressure of 10 mm. of mercury, which comprises admixing with the oil a petroleum distillate substantially all of which distils below 500° F. under atmospheric pressure, rapidly heating the mixture to a temperature in excess of that at which substantial cracking of the oil would occur if the mixture were permitted to remain at such temperature for a prolonged period of time, immediately thereafter separating from that portion of the mixture which remains liquid the vapors which form as a result of the heating aforesaid, then before substantial cracking occurs passing the liquid so separated 40 into a zone substantially devoid of the separated vapors, cooling it while in said zone to prevent cracking, fractionating the separated vapors by passing them countercurrent to a stream of reflux liquid oil, and drawing off a 45 portion of said reflux oil from contact with the vapor at a point in its course of travel.
